PNEUMATICALLY-CONTROLLED BLANK-TRIPPING MECHANISM FOR BLANK-FEEDING MECHANISMS.

1,244,537.

Specification of Letters Patent.

Patented Oct. 30, 1917.

Application filed February 8, 1916. Serial No. 76,990.

To all whom it may concern:

Be it known that we, MELVILLE E. PETERS, GEORGE H. FATH, and ALBERT F. MILLER, citizens of the United States of America, residing at the city and county of Denver and State of Colorado, have invented a new and useful Pneumatically-Controlled Blank-Tripping Mechanism for Blank-Feeding Mechanisms, of which the following is 10 a specification.

Our invention relates to a new pneumatically controlled blank tripping mechanism for blank feeding mechanisms; and the objects of our invention are:

15 First, to provide a mechanism that will stop and prevent a blank from feeding to the gumming rolls should it enter the machine slightly twisted out of straight alinement with the blank feeding and gumming mechanism, and that will automatically stop 20 the blanks if perchance two or more should be fed at one time into the machine. And

25 Second, to provide a tripping mechanism which will automatically trip a blank and prevent its being fed to the gumming rolls if by chance it enters the machine out of straight alinement with, and unless it enters the machine from its feeding mechanism in perfectly straight alinement with the 30 gluing rolls, and that will apply a coat of adhesive gum of predetermined thickness to evenly fed blanks.

We attain these objects by the mechanism illustrated in the accompanying drawings, 35 in which:

Figure 1 is a side elevation of a portion of our pneumatically controlled blank tripping machine, showing more particularly the connection between the vacuum pump and the feed roller, together with the operating mechanism, other parts being omitted.

40 Fig. 2 is an enlarged side view of a portion of the same side of the machine as shown in Fig. 1, and illustrating the combined blank tripping mechanism and feed roller operating mechanism.

45 Fig. 3 is a plan view of the parts shown in Fig. 2.

Fig. 4 is a front view, partly in section, of 50 the parts shown in Fig. 2.

Fig. 5 is a longitudinal sectional view

through a portion of the feed roller, illustrating the manner of connecting the suction box therein with the vacuum pump.

Fig. 6 is a side view of a portion of the 55 opposite side of the frame from that shown in Fig. 2, and illustrating the manner of supporting the feed roller with respect to the gumming cylinder and the manner of defining the limit of the rocking movement 60 of said roller.

Fig. 7 is a sectional view through the diaphragm mechanism which controls the action of the mechanism for actuating the feed roller. And

65 Fig. 8 is a fragmental side view illustrating a modification in the arrangement of the bearing supports for the feed roller.

Similar letters of reference refer to similar parts throughout the several views. 70

Referring to the drawings:

We illustrate therein in Figs. 1, 2, 3, and 4, general views of our apparatus embodying our invention.

Our invention is intended to trip up 75 blanks that feed into any machine to which our mechanism may be attached and especially blanks fed to blank or label gumming machines such as illustrated in our pending application Serial No. 30,471 filed May 25, 80 1915, for a new pneumatically controlled and automatically operating blank gumming and tempering machine. And also in our pending application, Serial No. 68,270, (now Patent No. 1,223,516,) filed December 85 22, 1915, for a coöperating blank feeding and gumming mechanism for blank gumming machines.

90 One of the essential elements of our blank tripping mechanism is a blank or label feeding roller 1. This blank or label feeding roller is an intermittently rotating roller and it comprises a hollow cylindrical roller which is mounted on a shaft 2. This shaft is supported in balanced tilting journal boxes 3, 95 which are formed on one end of a balanced rock arm frame 4, which normally holds the roller in an adjusted balanced position just close enough to the gumming cylinder to allow it to press a blank against the surface 100 of the gumming cylinder with a slight but decided pressure. Consequently these two

- cylinders are positioned nearly but not quite the thickness of a blank apart, which would be the nearest adjusted and set position of the feed roller to the gumming cylinder. 5 The feed roller has however a slight balanced reciprocal movement away from this adjusted and set position, by means of its balanced supporting frame, which is constructed as follows:
- 10 The two journal bearings 3 are formed at the end of arm portions 4, that project from a central body portion from which an arm 5 extends, on which a weight 6 is slidably and adjustably secured by a set screw 7. 15 The body portion extends across the machine between the side frames A and B of the machine, and a shaft 8 extends through the body portion and is secured to it and its ends are journaled in bearings formed in the 20 side frames. One end of this shaft extends beyond the side frame B and on its end a block 9 is secured. This block extends between two lugs 10 and 11 and set screws 12 and 13 are threaded from opposite vertical 25 directions through the lugs 10 and 11, and are adjusted to clamp the free end of the block 9 between them. This arrangement allows the free end of this blank to be adjusted and set in adjusted positions to 30 allow the journal bearings, the shaft and feed roller a balanced reciprocal movement of such a predetermined amount of distance to its normal position and distance from the gumming cylinder, as desired. This reciprocal 35 balanced movement of the feed roller, together with the balance movement of its supporting frame, will seldom exceed a thirty-second of an inch, and the feed roller is normally held and operatively rotates at 40 the thickness of or about the thickness of the blanks being fed through the machine to be gummed, it being understood that the feed roller must always force each blank with a slight pressure against the gumming cylinder, but at the same time the feed roller must 45 never touch the gummed surface of the gumming cylinder. The shaft 2 upon which the feed roller is mounted and secured, extends loosely through apertures formed through 50 the side frames A and B, without touching them, and its opposite ends are provided with apparatus that will be described hereinafter.
- The object of providing a reciprocating 55 relief movement to the blank feeding roller 1 away from and back to its normally set position is to enable it to be adjusted to feed blanks that may vary in thickness and also to yield away from its set position and from 60 the gumming cylinder, in case two or more blanks may perchance be accidentally fed to it and be carried by it to the gumming cylinder, and while we preferably illustrate and use this balance weighted support for the 65 feed roller and its shaft, we illustrate a sim-

pler arrangement of supporting the feed roller, which is automatically controlled to move away from and back to its set position enough less than the distance of the thickness of the blanks being fed from the surface of the gumming cylinder, to press the blanks normally against the surface of the gumming cylinder. In this modified arrangement, the shaft is rotatably journaled in boxes 14 that are slidably mounted in 75 guideways 15 that are formed in the side frames A and B of the machine, and which are provided with an expansive spring 16 against which the boxes bear, and with a stud screw that is threaded to the frame. 80 This stud 17 is provided with adjusting nuts that permit the sliding boxes and the feed roller to be placed under the desired reciprocating resilient tension to allow the feed roller to reboundingly yield from its set positions relative to the gumming cylinder 20. 85

The hollow feed roller 1 is provided with a narrow air suction blank gripping and conveying device 18 that is secured along the edge of a gap, that is formed in said roller nearest to the automatic blank feeding mechanism of the machine, and this air-suction device is provided with a row or line of air suction apertures 19 that extend along its length, which are arranged and adapted to receive and grip by an air suction force the advancing edge of each blank as it is fed to this feed roller. In order to conveniently receive the blanks from the blank feeding mechanism, the feed roller is timed to stop 90 or hesitate in its intermittent rotative movement when its line of air suction apertures register in alinement with the vertical axis of the feed roller, and as it stands in its stopped position at the end of each revolution, the advancing edge of each blank is fed directly onto this line of air suction apertures that form a part of the automatic blank feeding mechanism, by a movable air suction device, which will be presently described. 100

This feed roller 1 is however the first member of our gumming machine to receive a blank, and while we have preferably illustrated and used our machine equipped with 115 an automatic blank feeding device, which we have especially designed for it, our gumming machine contemplates broadly any and every and all types of blank feeding machines and devices that are suitable for feeding blanks to it. 120

This feed roller 1 is geared and timed to make a full revolution and then to stop or hesitate in its turning movement long enough to allow a blank to be fed to its line 125 of suction apertures, and it is timed to always make the full revolution including the stop in the same time the gumming cylinder makes one of its full continuous revolutions, and the feed roller is also so relatively 130

timed to each revolution of the gumming cylinder, that its line of blank gripping suction apertures will grip, feed and deliver the advancing edge of each blank against 5 and along the advancing edge portion of the reciprocating segment of the gumming cylinder, and as this segment together with the entire surface of the cylinder is covered with a thin coat of gum, the blank when pressed 10 against the segment of the cylinder receives an even coat of gum along its advancing edge that is on the segment, as well as throughout its entire surface of its side that is pressed against the surface of the gumming cylinder by the rotating feed roller as the surface of the gumming cylinder including the entire surface of its gap filling segment is completely covered at all times with a thin even coat of adhesive liquid 15 gum, which it received from the gum distributing roller 21, which supplies the gumming cylinder with gum. Consequently when the feed roller feeds and presses a blank against the surface of the segment of 20 the gumming cylinder, its advancing edge instantly sticks to the gummed surface thereof, and as the rotating feed roller rolls the blank off and against the surface of the gumming cylinder, the blank is wrapped 25 and stuck to the gummed surface of a portion of its surface, as the cylinder rotates, and it is thus at the same time that an even coat of gum is being pressed on one side of it, being carried and fed forward by the 30 gumming cylinder to the point where its segment flies back into the cylinder and opens the gap, which exposes the advancing edge of the blank to the action of the pickers, which instantly grab it and peel it off 35 in the direction it would naturally curl up in, and conveys it instantly to the tempering mechanism, which moistens its opposite side from its gum coated side and then discharges it in a position while it is in a 40 limpid tempered condition to a point where it can be instantly fed to any operative box covering machine. Consequently each blank as it is fed forward and discharged from the gumming cylinder is coated and covered 45 on one of its sides with a coat of gum, which coat of gum may by proper manipulation of the gum distributing roller 21 be of any predetermined and desired degree of thickness. 50 The intermittent blank gripping, holding, feeding and releasing air suction device of the feed roller may be of any desired construction and arrangement, as our invention in this respect contemplates broadly any air 55 actuated device or mechanism that will grip, hold, move and release at a predetermined point in the rotative movement of a blank feeding roller a box covering blank. We employ in connection with the feed 60 roller 1, an air suction holding and releas- ing device for feeding the blanks to the gumming cylinder. This air suction device comprises a thin hollow square shaped strip of metal 18, that is detachably secured to the edge of the gap by screws 22, and through 65 the top of this box a row of small air suction inlet apertures 19 is formed, in a straight line parallel with the longitudinal axis of the feed cylinder. These air suction apertures 19 may be positioned at any desired distance apart throughout its length, it only being necessary to use enough of them positioned close enough together and at equal distances apart to firmly grip and hold to the blanks by the air suction force 70 of an air pump. 75 This air box is provided with a longitudinal chamber 23, into which each of the air suction apertures extend, and centrally of its length it is provided with an inlet nipple aperture 24, to which one end of a tube 25 is secured. The opposite end of this tube extends to a nipple 26 that is threaded into an aperture formed in the shaft 2 within the feed roller 1 near its left flange 27, where it intersects an axial aperture 28 formed in the left hand end of the shaft. A hollow cap 29 is secured to the end of this shaft from which a nipple portion 30 depends that terminates in a T fitting 31, from 80 which a nipple member 32 extends horizontally and is connected to one end of a short piece of rubber tubing 33, the opposite end of which is connected by a pipe 34, to an air pump cylinder 35. This air pump is provided with a piston that is reciprocated by a cam 36 and lever mechanism 37. The cam is mounted on a shaft 38, which is driven by a clutch controlled driving worm shaft 39 and pulley 40 and worm driven wheel 41 by and from which the entire machine is 85 operated. A nipple 42 is connected to the opposite end of the T 31 and terminates in an elbow from which a pipe 43 extends across both of the side frames A and B of the machine, and is connected by a tube 44 to the inlet nipple 45 of an air suction diaphragm 46 which forms a part of the blank tripping mechanism, which will be presently described. 90

This blank gripping, feeding and releasing suction box is made long enough to receive and feed the longest blanks the machine will gum, and the machine will gum all sizes of blanks used for covering boxes 95 from about 3½ inches long by varying widths, up to between nineteen and twenty inches long and of varying widths, and when gumming blanks that are not wide enough to cover all of the air suction apertures in the suction box, those at the ends of the suction box not covered by the blank must be closed, and we have made provision to close all of the air suction apertures 100 on each side of the center of the length of 105

We employ in connection with the feed roller 1, an air suction holding and releas- 110

115

130

the suction box that are outside of and are uncovered when using the smallest sizes of blanks that the machine will coat with gum.

While various means could be employed for closing these air suction apertures, we preferably carry out this feature of our invention in the following manner:

This blank gripping suction box is provided along its accessible side in the gap of and within the feed roller commencing beyond those centrally located air suction apertures which would receive the narrowest blanks that would be run and gummed by the machine, with apertures 47 that extend transversely through the air suction box, and each of which is positioned to intersect one of the air suction apertures and in each transverse aperture a finger operating plug valve 48 is secured, which is arranged to open or close these air suction apertures. Consequently all air suction apertures that are outside of the size of blanks being run through and gummed by the machine are closed, and it is necessary that they should be closed because if one air suction aperture beyond a blank is left open, the suction is broken and the suction grip and hold are broken and rendered inoperative, and even when blanks that are wide enough to cover all of the air suction holes are fed into the machine in such an uneven and twisted condition as to expose one of the air suction apertures on either end of the suction box, the suction grip does not take place, as the vacuum is broken and the feed roller will not move and will miss its revolution, and will stand still until a blank is fed to it in a straight position. Then the advancing edge of the blank is placed over all of the air suction apertures and they instantly grip and hold it firmly down against the air suction box.

The automatic blank tripping device is adapted to trip up or break the air suction force of the feed roller by rendering it instantly inoperative, and it also operates to lock the feed roller against rotation when a blank feeds to the suction box in such a crooked, uneven, or partially folded or in any other way out of proper order and position to fully cover all of the air suction apertures of the suction box, or in other words, when a blank feeds so out of straight alignment or wrinkled to the longitudinal plane of the line of air suction apertures and to the longitudinal axis of the feed roller, that one or more air suction apertures 19 are left uncovered at either one or both ends of the air suction box, and inasmuch as the blanks feed into and through our machine at the rate of about fifty per minute, the tripping mechanism employed must act quickly and be controlled automatically by the continuous rotating movements of the gumming cylinder. This is

essential, as the principal object of this trip is to arrest and stop the out of order blanks before they reach the gumming cylinder and clog it and the entire machine, which would necessitate stopping the machine and removing the clogging blank and cleaning the gumming cylinder.

Consequently our invention contemplates a pneumatically operating apparatus co-operating with means connected to and controlled by the gumming cylinder and the feed roller, that will trip up and stop blanks that are in any way out of order when they first reach the feed roller, which is the threshold of the machine, as the surest way of preventing their reaching the gumming cylinder.

Our invention in this respect contemplates any and all pneumatically operated apparatus co-operatively united with the machinery connected with the blank feeding and gumming mechanism of blank gumming machines. We preferably however carry out this feature of our invention in the following manner:

The air suction diaphragm 46 to which the air tube which leads from the T fitting 31 and the air pump 35, is connected, comprises a saucer-shaped disk 47^A over which a diaphragm of flexible material, preferably leather, 48 is secured, which is clamped to the disk by a ring-like member 49, that is secured to the disk by screws 50. The diaphragm disk has a hub portion 51 which is provided with a chamber 52, in the inner end of which a sleeve 53 is slidably mounted. The bottom of this sleeve is provided with apertures that admit air from the diaphragm to its hub's chamber. A stem 54 is threaded to the sleeve, which passes through the diaphragm. This stem is provided with a nut that clamps the diaphragm against a collar shoulder 55 formed on the stem. This stem extends to and through and is slidably connected to the lower end of a rock arm 56. The opposite end of this rock arm 56 is adapted to operate a hub 57, which is slidably mounted on and is feather keyed to the shaft 2, that the feed roller is mounted on. This hub is provided with an annular groove 58, in which a segment of a collar 59 fits loosely, and that is secured to the upper end of the rock arm 56, by a cap screw 60. This hub 57 forms the supporting part of a locking bolt 61, and the rock arm is arranged and adapted to move the locking bolt through the medium of this collar segment bearing in the annular groove of the hub of the locking bolt out of locking engagement with a key-way recess 62, that is formed in the adjacent face of an adjacent spur gear 63, as will be presently described, and this locking bolt is held normally against the face of the gear as the gear rotates when the locking bolt is not

locked to it, by an expansive spring 64, which is mounted on the end of the shaft 2, and is confined there by a collar 65, that is secured to the end of the shaft by a set 5 screw. Consequently this expansive spring holds the locking bolt in operative locking position to the locking recess of the gear, in which the locking bolt is adapted to fit loosely, while the upper end of the rock arm 10 when moved by mechanism to be presently described that co-operates with the diaphragm and its reciprocating stem 54, moves the locking bolt's hub to unlock the locking bolt from the recess in the spur gear. The 15 spur gear 63 is an intermittently rotating gear, it being made so by leaving several of its teeth off and forming in their place a smooth curved portion, 67, that registers with a similar smooth portion on its driving gear. 20 This intermittently rotating gear is loosely mounted on a hub 68, that surrounds the feed roller's shaft 2, loosely enough to allow this shaft to move or float on its swinging bearings on it, as the feed roller has an 25 adjustable reciprocal balanced or floating movement toward and away from the surface of the gumming cylinder, as above described, and this shaft 2 also has a free balanced or floating movement in the apertures of the frame, and in this hub 68, which 30 is secured to the side frame A by cap screws 69. Consequently this intermittently rotating gear is an idler gear and is mounted on the hub 68, and the feed roller and its 35 shaft has a floating movement in this hub entirely independent of the rotative bearing of the intermittently rotating spur gear 63, that drives them through the medium of the locking bolt that is feather-keyed to 40 the shaft 2 of the feed roller.

The rock arm 56 is pivotally supported intermediate of its ends by a bolt 70, to a yoke-shaped bracket 71, that is bolted to the adjacent side frame of the machine. The 45 smooth curved peripheral surface 67 on the periphery of this intermittently rotating gear 63, is made of such a predetermined part of its circumference as will cause the gear to stop dead or hesitate during each 50 of its revolutions, and as this gear drives the blank feeding roller it controls and determines the length of time the feed roller or more strictly speaking the air suction box shall stop at its blank receiving station to 55 receive each blank from its automatic blank supplying and feeding mechanism relative to the time in which the feed roller makes its full revolution.

We have found in practice that a stop at 60 the blank receiving station of the air suction box of the feed roller is advantageous, as it prevents blanks that are out of orderly arrangement with the line of air suction apertures of the air suction box from ever 65 starting toward the blank gumming cylinder

until it has been put into orderly alinement with the line of blank gripping air suction apertures of the air suction box of the feed roller.

The length of time that the air suction box does stop at its blank receiving station is just sufficient to allow the blanks to be fed to and its advancing edge to be placed over the air suction apertures which are under suction draft ready to receive it, and if it covers all of the air suction apertures, to grip it, then start forward with it and feed it to the gumming cylinder. If, however, the advance edge of the blank does not cover all of the air suction apertures of the air suction box and even only one or a part of one is exposed to the atmosphere, the suction will be broken in the air suction box of this feed roller, and will fail to act in the air suction diaphragm, and the blank will 70 stop at this air suction box until this particular blank is either righted into alinement so as to fully cover all of the suction apertures under it and within the scope of the area of its advancing edge portion, or else 75 to remove it entirely from the machine, and this may be accomplished by an automatically operating mechanism which forms no part of our present invention, and which is 80 therefore not illustrated.

The diaphragm disk 47 itself is secured to the rock arm 56 by three stud screws, one of which secures it to the adjacent side of the rock arm 56, and the other two, which extend from opposite sides of the diaphragm, are secured to the ends of two arms 72, that are projected from opposite sides of the rock arm to receive them. Consequently this diaphragm rocks with the rock arm. The stem 54 of the diaphragm is provided 100 with a collar portion that bears against the adjacent side of the rock arm 56, while the stem extends loosely through the rock arm and terminates in a pin portion 73 that projects beyond it into engaging and disengaging relation to a swinging lever, as will 105 be presently described.

The air chamber in the hub of the diaphragm disk is provided with an expansion spring 74 which bears against a cup portion 110 of the air inlet nipple 45 at one end, and against the bottom of the sleeve 53 at its opposite end. This spring holds the diaphragm stem and the flexible diaphragm extended out to the limit of its outward movement, while the air suction of the air pump 35 draws the diaphragm in against the tension of the spring, and when the suction force is cut off, the spring moves the sleeve, its stem, and the diaphragm out again to 115 their normal positions, in front of the bearing side 75 of a swinging lever 76, which would then engage it if it remained there. When, however, the suction impulse does act on the diaphragm, the pin is drawn back 120 to 125 130

out of the swinging path of the lever 76 which then swings past the pin 73. These relative positions of the bearing end of this lever 76 will be more fully explained herein-after.

6 The swinging lever 76 is mounted on and secured to one end of a rock shaft 77, which is journaled in the lower ends of the bracket 71; the lower end of this lever is provided with a flat bearing surface that is slightly inclined upwardly and forwardly toward the machine, in order that it may have a squarer contact against the pin during its pushing stroke against it.

15 A lever 78 is connected to the opposite end of this rock shaft, which is connected by a link 79 to one end of a rock arm 80, the opposite end of which is provided with a roller 81, that engages a cam 82, that is formed on the outside surface of a spur gear 83, that is bolted to the face of a gear 84, which is secured to the shaft 85 of the blank gumming cylinder, which rotates continuously. Consequently the shaft gear drives the spur gear 83 continuously.

25 The rock arm 80 is pivotally secured by a pivotal bolt 86 to a lug portion 87 on the upper adjacent end of the bracket 71. The cam 82 is a raised ring member that is formed 30 on the side of the spur gear 83, and at one point it is provided with a recess 88, into which the roller 81 of the rock arm 80 moves, being forced therein by a coiled spring 89, with which the rock shaft 77 is provided. One end of this spring is secured to the bracket 71 and the opposite end is secured to a collar 90, that is mounted on and secured to the rock shaft by a screw. This spring 89 is arranged and adapted to 40 hold the roller end of the rock arm in continuously bearing contact with the surface of the cam 82, and to force it into its recess 88, so that this rock arm may have a positive reciprocal and continuous oscillating movement which is imparted to the rock shaft 45 through the lever 78, and through the rock shaft 77 to the swinging oscillating lever 76, and these rock arms 76 and 78 swing and oscillate regardless of the reciprocal movement of the pin end 73 of the stem 54, due to the air suction impulses of the diaphragm in drawing the pin out of the path of the swinging lever or of its forward movement into the swinging path of the lever, due to 55 the action of the spring 74 within the diaphragm.

The pin normally stands in the path of the swinging lever's sloping end 75, but the diaphragm will always withdraw the pin out of the path of the end 75 of the swinging lever as long as blanks are fed to the suction box of the feed roller in straight proper order of alinement relative to the line of air suction apertures in the suction box of the feed roller, but the instant a blank feeds to

the line of air suction apertures in the suction box and does not cover all of its air suction apertures, the suction is broken both in the air suction box and in the diaphragm, and then the spring 74 of the diaphragm 70 throws or pushes the pin across the path of the swinging lever, which engages it and swings it along with its stroke toward the adjacent side frame A of the machine, which tilts the diaphragm and its rock arm, as will 75 be presently described.

The above described movements are the regular natural actions of the diaphragm and the rock lever 56, the rock arm 80 and the cam, on the continuously rotating spur gear 83, and it affects the intermittently rotating gear 63, which is mounted loosely on the hub 68, but which rotates the shaft 2, of the feed roller, and the feed roller itself, as follows: Whenever the diaphragm 48 receives 80 suction force impulse action from its air pump, 35 the suction box of the feed roller also receives a suction force impulse simultaneously, as they are in synchronous relation, and they always receive such an impulse 85 with every blank that is fed straight to the suction box of the feed roller, and covers all of its air suction apertures 19, and when the diaphragm receives this suction impulse its pin is withdrawn out of the path of the 90 swinging lever 76, and as a consequence its own lever 56 is not moved to draw the locking bolt out of its recess in the intermittently rotating idler gear 63 and consequently the locking bolt rotates with this 95 spur gear 63, which on account of its being an idler that is loosely mounted on a hub 68, that loosely surrounds the shaft 2 of the feed roller, does not rotate the feed roller because the hub 68 is secured to the side 100 frame A. Consequently the intermittently rotating gear 63 does not directly drive the feed roller 1, but it drives the locking bolt 61 around with it, which is feather-keyed to the shaft 2 of the feed roller and consequently the feed roller is rotated by the locking bolt through the medium of this intermittently rotating idler spur gear 63, and the feed roller is in this manner rotated with 105 every blank that is fed to it in such order as 110 to completely cover all of the air apertures of its suction box that are under the size of blanks being run through the machine, and all of those apertures that are not under the size of blank being run are tightly closed 115 by the finger valves 48.

When however a disorderly blank is fed to the air suction apertures of the air suction box, as occasionally happens, considering the large number of blanks our machine 125 will gum in a day, which is about fifty a minute, and the disorderly blank is out of alinement with the row of air suction apertures in the suction box enough to leave even a part of one air suction aperture at either 130

end of it uncovered, the suction vacuum in the suction box and also simultaneously in the air suction diaphragm of the trip mechanism, is broken, as they are both operated 5 in unison by the one air pump 35. Then the instant the air suction is broken, the diaphragm will not move and its pin is not withdrawn from the oscillating path of the swinging lever 76, and consequently the 10 swinging lever engages it and swings it along with it, which movement causes the lower end of the rock arm 56 and also the diaphragm to move with the pin and it causes the upper end of the rock arm to 15 move laterally away from the mutilated gear 63, and in doing so to draw the locking bolt out of the key-way or recess 62 in the side of the gear, and the hub of the locking bolt slides back on its feather-key under the pressure 20 of the segment collar of the rock arm in its annular groove. The locking bolt 61 is now withdrawn from and free of the mutilated idler gear 63. Consequently while this gear continues to rotate, being driven 25 by the gear 83 on the shaft of the gumming cylinder, which is rotating continuously, the feed roller's shaft 2 which is under the control of the locking bolt is stopped and consequently the feed roller is stopped, and as it 30 will not move and feed the crooked blank, this blank is tripped up or stopped, and before it has entered the machine far enough to do any damage or cause any unusual delay, but it must be immediately either re- 35 moved or squared around to cover the one or more air suction apertures it failed to cover when it was fed in a crooked condition to the suction box of the feed roller. It requires but a few seconds of time to remove crooked 40 blanks, which will immediately start the suction box and diaphragm suction impulse in their regular operative order, the suction box gripping the blanks and the diaphragm simultaneously withdrawing its pin out of 45 the path of the swinging lever and allowing the gear to drive the locking bolt and feed roller to make its revolution.

Our invention provides a reliable trip mechanism that operates to trip up and 50 stop blanks that feed to the feed roller in an irregularly alined condition, and while we have illustrated and described the preferred construction and arrangement of our blank tripping mechanism, we do not wish 55 to be limited to it as many changes might be made in it without departing from the spirit of our invention.

Having described our invention, what we claim as new and desire to secure by Letters Patent, is:

1. In a blank tripping mechanism for paper blanks for blank gumming machines, a blank feeding roller having a blank gripping suction mechanism, means for intermittently rotating said feed roller when a

blank is properly gripped by said suction mechanism, and means for locking said roller against rotative movement when a blank is not gripped by suction.

2. In a blank tripping mechanism for 70 paper blank gumming machines, a blank feeding roller provided with means including air suction blank gripping apertures through its surface arranged in transverse alinement, means for intermittently rotating said feed roller, and means including a cam actuating combined suction and mechanically operating mechanism for stopping and locking said feed roller in a position for its suction means to properly grip 80 and hold a blank by suction, said suction operating means being arranged to hold said feed roller in a locked position when its suction fails to grip a blank.

3. In a blank tripping mechanism, the 85 feed roller provided with a transversely alined row of air suction inlet apertures adapted to grasp and hold a blank, the blank gumming cylinder and the cam actuated means operated by said cylinder and 90 including the combined suction and mechanical operating mechanism for locking said feed roller intermittently.

4. In a blank tripping mechanism, the 95 combination of the blank feeding roller, the gumming cylinder, the cam controlled air suction diaphragm mechanism for the feed roller actuated and timed by said gumming cylinder's rotating movement.

5. In a blank tripping mechanism, the 100 combination of the blank feeding roller and its supporting shaft, the gumming roller and its supporting shaft, the mutilated gears on said shafts, and means including cam and lever actuated mechanism and an air 105 suction diaphragm spring controlled in one direction of its movement for intermittently stopping said feed roller at a predetermined blank receiving part in its rotative movement.

6. A combined pneumatically and mechanically operating blank tripping mechanism for blank gumming machines, comprising a blank gumming cylinder, a feed roller provided with a blank gripping air 115 suction mechanism, and means including adjustable bearings for setting said feed roller in blank feeding relation to said gumming cylinder, and means including an air suction mechanism for operatively feeding 120 properly alined blanks by said roller to said gumming cylinder and for stopping disorderly alined blanks at said feed roller's air suction blank gripping mechanism.

7. A combined pneumatically and mechanically operating blank tripping mechanism for blank gumming machines, comprising a blank gumming cylinder, a feed roller provided with a blank gripping air 125 suction mechanism, means including adjust- 130

able bearings for setting said feed roller in blank feeding relation to said gumming cylinder, means including an air suction mechanism for operatively feeding properly 5 alined blanks by said roller to said gumming cylinder and for stopping disorderly alined blanks at said feed roller's air suction blank gripping mechanism, said means including cam actuated lever mechanism 10 controllable by said feed rollers and said gumming cylinder's rotary movement.

8. In a blank tripping mechanism for gumming machines, adjustable means for gumming and regulating the coat of gum 15 on the blank, means for feeding the blank to the gumming means, suction producing means operated jointly by the gumming and feeding means for controlling the blank feeding action, means for operating the 20 feeding means, means for interrupting the suction means, and an operative connection between the suction producing means and the interrupting means to render the latter inactive as long as the suction acts effectu- 25 ally on the blank.

9. In a blank tripping mechanism for blank feeding machines, the combination with a blank feeding cylinder, of means including a blank feeding roller having perforations extending through its face and 30 adapted to be covered by the blank, suction producing means connected with the feed roller and acting on the blank through the perforations of the roll for blank retaining 35 purposes, means for operating the feed roller, means for automatically interrupting the connection function of the feed roller immediately prior to the beginning of the blank feeding act of the roller when a 40 blank is not in orderly alinement with said perforations, and an operative connection between said suction producing means and the interrupting means to render the latter inoperative as long as the suction acts on 45 the blank through the perforations of the roller to properly grip and feed the blank.

10. In a blank tripping mechanism for blank gumming machines, the combination with a blank gumming cylinder, of a blank 50 feeding roller whose face is provided with a perforated segment, air suction producing and blank gripping means acting through said perforations to retain the blank in place during the feeding act, means for rotating 55 the blank feeding roller, means connected with said gumming cylinder for automatically interrupting the connection between the blank feeding roller and its operating blank suction gripping means at the begin- 60 ning of the blank feeding act of the feed roller, and an operative connection between the blank gripping suction producing means and said interrupting means of the gum- 65 ming cylinder whereby the feed roller re- mains inactive when the suction is in force.

11. In a blank tripping mechanism for blank gumming machines, a blank feeding roller, suction producing means connected to said roller for retaining the blanks in their operative feeding position during the 70 feeding act, said roller being perforated to allow the suction to act on the blank through said perforations, means for operating the roller, means for interrupting the connection between the roller and its operating 75 means immediately before the commencement of the blank feeding act of the roller when a blank is not in operative alinement therewith, and an operative connection be- 80 tween the suction producing means and said interrupting means, whereby the latter re- mains inactive when the suction is in force.

12. In a blank tripping mechanism for blank feeding or gumming machines, the combination with a supporting frame, of a shaft supported blank feeding or gumming cylinder, said cylinder being provided with an openable and closable peripheral gapped surface portion adapted to receive and expose the advancing edges of blanks either without 90 gum or coated with gum, a blank feeding shaft supported roller having a blank receiving station, and an air suction producing mech- 95 anism for gripping a blank at said station, a mutilated gear on said cylinder's shaft, a mutilated gear on said feed roller's shaft 100 registering with the mutilated gear of said feed cylinder's shaft, means including a cam controlled rock arm mechanism operated by said cylinder's shaft and cylinder and co- 105 operating with an air suction operating dia- phragm controlled mechanism cooperatively controlled by said feed roller and its mutilated gear and shaft and operatively connected to said air suction producing blank 110 gripping and releasing mechanism for grip- 115 ping, holding, releasing, and feeding to said gumming cylinder all blanks that are in proper order of alinement when fed to said feed roller's blank receiving station, and for 120 tripping up and stopping at said blank re- ceiving station all blanks not in proper order of alinement.

13. In a blank tripping mechanism for gumming machines, gum supplying and distributing rolls and a blank gumming cylinder for gumming the blanks, a blank feeding roller for feeding the blanks to the gum- 125 ming cylinder, suction-producing means act- ing through the feed roller which is perforated for the purpose of retaining the blanks in place during the feeding act, the arrange- 130 ment being such that when the blank is properly positioned all the perforations are covered, and the suction is effective, means for operating the feed roller to feed blanks to the gumming cylinder, means for inter- 135 rupting the connection between the feed roller and its operating means immediately prior to the beginning of the normal blank 130

feeding act of the feed roller, and an operative connection between said suction-producing means to prevent the interrupting means from acting when the suction is intact.

14. In a blank tripping mechanism for gumming machines, the combination with gum supplying and gum distributing mechanism, means for feeding blanks, and a low gum distributing cylinder, having an opening and closing segment portion, a main feed roller operating gear, a second gear meshing with the main gear mounted coaxially with the roll and normally loose, means including a crank arm feather-keyed on the shaft of the feed roller and normally spring-held in key locked relation with the loose gear to cause the rotation of the latter to operate the feed roller, means for interrupting the connection between the feed roller and its blank gripping suction mech-

anism at the beginning of the blank feeding act of the feed roller, a rock arm for shifting the crank arm, a flexible diaphragm connected to said rock arm, a pin arranged to be moved by said diaphragm as said diaphragm vibrates by air suction impulse action, a cam carried by the main gear, a crank arm actuated to swing reciprocally by said cam and into the operating path of said pin, and a spring for normally holding said pin normally in the path of said cam operated swinging crank arm.

In testimony whereof we affix our signatures in presence of two witnesses.
